UNITED STATES PATENT OFFICE.

CLAUDE B. STILLWELL, OF JACKSONVILLE, FLORIDA, ASSIGNOR TO HIMSELF AND JOHN C. LITTLE, OF JACKSONVILLE, FLORIDA.

CLOSURE.

No. 877,805.

Specification of Letters Patent.

Patented Jan. 28, 1908.

Application filed July 29, 1907. Serial No. 386,075.

To all whom it may concern:

Be it known that I, CLAUDE B. STILLWELL, a citizen of the United States, and resident of Jacksonville, in the county of Duval and State of Florida, have invented a new and Improved Closure, of which the following is a full, clear, and exact description.

This invention relates to closures for different types of vessels and is particularly useful in connection with bottles and the like.

An object of this invention is to provide a simple, strong and durable closure for vessels, such as bottles and the like, which has means permanently attached thereto for withdrawing the closure from the mouth of the vessel without the aid of a corkscrew, or other device for a like purpose.

A further object of the invention is to provide a closure or stopper of the class described, having the extracting means partially embedded and anchored in the body of the closure, in such a manner that no part of the extractor comes in contact with the contents of the vessel.

A still further object of the invention is to provide a closure with a suitable extractor for withdrawing the same from the mouth of a vessel without injuring or destroying the stopper.

The invention consists in the construction and combination of parts to be more fully described hereinafter and particularly set forth in the claims.

Reference is to be had to the accompanying drawings forming a part of this specification in which similar characters of reference indicate corresponding parts in all the figures in which

Figure 1 is a longitudinal section of the closure, showing the same applied to a necked vessel; Fig. 2 is a transverse section on the line 2—2 of Fig. 1, showing the closure removed from the vessel; Fig. 3 is a transverse section showing a closure of modified form; Fig. 4 is a longitudinal section, showing a further modified form; and Fig. 5 is a longitudinal section of a closure of a still further modified form.

Before proceeding to a more detailed description, it should be said, that while I preferably employ a stopper of cork, rubber or the like, my invention is applicable to different kinds of closures. In connection with the closure, I use an extracting device by means of which the stopper may be readily

removed from the vessel. This extracting device is suitably mounted within the body of a stopper and is securely held in place by cement or other suitable means. The lower end of the extractor is bifurcated and constitutes an anchor which co-acts with the cement or other material to hold the extractor rigidly in position. By this arrangement is obviated all danger of injury to the stopper itself in withdrawing the same, as the strain incident to the removal of the closure is distributed by the extractor and the anchoring material.

Although I have represented my improvements in a certain preferred embodiment it should be understood that I am not limited to the precise details as described.

Referring more particularly to the drawings, 1 represents the neck of a vessel into which the closure fits. 3 represents an opening in the stopper 2 of preferred or common form. The opening 3 is of suitable size and depth to receive an extractor which serves to withdraw the stopper from the neck of the vessel. The extractor 4 is preferably fashioned from an elongated body, such as wire, cord, twine, and the like, and comprises a shank 5, formed by twisting lengths of the body together, an eye 7 at one end of the shank, and laterally disposed prongs 6 at the opposite ends thereof. The prongs 6, together with the stem 5, are arranged in the opening 3, and are secured in position therewith by means of a cementing material, such as sealing wax, cement, and the like. The stem and prongs are held in rigid position by the cement or other suitable material, and constitute an anchor for the extracting device. The cementing material in the opening should fill the same partly, leaving a recess in the top of the stopper into which the eye of the extractor can be depressed into an inoperative position. The opening 3 may be of any suitable form, such as that of the rounded opening in Fig. 2, or that of the angular opening illustrated in Fig. 3. In the modified form as shown in Fig. 4, I employ plugs 9 of wood, or other suitable material, arranged within the openings, adjacent to the stem and engaging the prongs 6.

In Fig. 5, is shown an extractor consisting of a ring member 10, a twisted body portion 11, to which the ring member 10 is attached, and elongated members 12, integral with the body portion 11.

I desire to reiterate, that my invention does not reside in certain structural features shown herewith, but that the principle thereof consists in the application of an extractor, 5 anchored in position by means of an adhesive or cementing material, to a stopper, in such a manner that the extractor is not in direct engagement with the body of the stopper.

Having thus described my invention, I 10 claim as new and desire to secure by Letters Patent:

1. A closure, comprising a stopper, an extractor, and plastic means adapted to harden and serving to secure said extractor to said 15 stopper.

2. A closure, comprising a stopper, said stopper having an opening adapted to receive an extractor, and plastic means for rigidly mounting said extractor in said opening, 20 said plastic means hardening on exposure.

3. A closure, comprising a stopper, an extractor, said stopper having a suitable opening to hold said extractor projecting from said opening, and plastic means for securing 25 said extractor in position, said plastic means being adapted to harden after said extractor is in position.

4. A closure, comprising a stopper, an extractor carried by said stopper having a grip 30 at one end thereof, an anchor at the other end of said extractor, and plastic means adapted to harden and serving to secure said anchor in position at said stopper.

5. A closure, comprising a stopper presenting an opening, an extractor provided 35 with an anchor adapted to be mounted within said opening, plastic and means for holding said anchor within said opening and out of engagement with said stopper.

40 6. A closure, comprising a stopper presenting an opening, an extractor provided with prongs constituting an anchor adapted to be

mounted within said opening, and means for holding said anchor within said opening and out of engagement with said stopper; said 45 means consisting of a plastic material adapted to harden.

7. A closure, comprising a stopper presenting an opening, an extractor provided with prongs constituting an anchor adapted 50 to be mounted within said opening, and a plastic material within said opening and holding said anchor from engagement with said stopper, said material partially filling said opening and adapted to harden.

8. A closure, comprising a stopper presenting an opening, an anchor formed from an elongated body having parts entwined to form a stem and provided with a grip and prongs at the ends respectively of said stem, 60 said stem and said prongs constituting an anchor adapted to be mounted within said opening, and plastic means adapted to harden and serving to hold said anchor in position.

9. A closure, comprising a stopper presenting an opening, an anchor formed from an elongated body having parts entwined to form a stem and provided with a grip and prongs at the ends respectively of said stem, 65 said stem and said prongs constituting an anchor adapted to be mounted within said opening, and plastic means adapted to harden, 70 and serving to hold said anchor in position, said plastic means partially filling said opening and holding said anchor out of engagement with said stopper.

In testimony whereof I have signed my name to this specification in the presence of two subscribing witnesses.

CLAUDE B. STILLWELL.
